UNITED STATES PATENT OFFICE

162,556

TEXTILE FABRIC

Sonia M. Mandell, New York, N. Y., assignor to Marcus Brothers Textile Corp., New York,
N. Y., a corporation of New York

Application January 3, 1950, Serial No. 6,965

Term of patent 3½ years

(Cl. D92—1)

To all whom it may concern:

Be it known that Sonia M. Mandell, a citizen of the United States of America, and resident of the Borough of Manhattan, city and State of New York, has invented a new, original, and ornamental Design for Textile Fabric, of which the following is a specification, reference being had to the accompanying drawing, forming part thereof, in which the figure is a plan view of a textile fabric embodying my new design.

The dotted lines on the drawing outline substantially a design unit, which unit is repeated in regular succession as indicated by the extensions beyond the unit boundaries.

I claim:

The ornamental design for a textile fabric, substantially as shown and described.

SONIA M. MANDELL.
